COMBINED BRAKE LAMP AND LATERALLY DIRECTED MIRRORS FOR MOUNTING ON THE FRONT OF A VEHICLE

Hwabong Lee, 2834 3-chome, Tokyo, Japan

Filed May 4, 1965, Ser. No. 85,128

Term of patent 14 years

(Cl. D48—32)

FIG. 2

FIG. 1

FIG. 3

FIG. 5

FIG. 4

FIG. 6

FIG. 7

FIG. 1 is a front elevational view of a combined brake lamp and laterally directed mirrors for mounting on the front of a vehicle showing my new design;

FIG. 2 is a top plan view thereof;

FIG. 3 is a left-side elevational view thereof;

FIG. 4 is a rear elevational view thereof;

FIG. 5 is a bottom plan view thereof;

FIG. 6 is a cross-sectional view taken on line 6-6 of FIG. 2; and

FIG. 7 is a front perspective view thereof.

I claim:

The ornamental design for a combined brake lamp and laterally directed mirrors for mounting on the front of a vehicle, substantially as shown.
